(57) **CLAIM**

The ornamental design for a garment, as shown and described.

DESCRIPTION

FIG. 1 is a rear view of a garment showing our design; FIG. 2 is a rear perspective view thereof; and, FIG. 3 is a top view thereof.

The claimed area is limited to the shaded areas enclosed by solid lines. The unshaded areas form no part of the claim. The even-length broken lines are directed to environment, represent unclaimed subject matter, and form no part of the claim.
